Knitting Mills, Inc., Knoxville, Tenn., a cor-
poration of Tennessee

Application November 27, 1945, Serial No. 631,043

4 Claims. (Cl. 2—224)

1

This invention relates to below-the-waist undergarments, and has particular application to support type shorts, briefs and drawers for male wear.

One of the principal objects of the invention is to provide an improved form of undergarment embodying the support feature which is better fitting than previously known garments of the same general type, and which affords sufficient fullness in the crotch and thigh regions to allow complete freedom of body movement without binding or discomfort.

Another object is to provide a nether garment of the character described having a novel form of crotch construction which not only furnishes extra material and elasticity where needed to accommodate all normal movements of the body, but also provides a well supported pouch at the crotch.

A further object is to provide an undergarment of new construction wherein the advantages of better fit, maximum comfort and an improved pouch formation are economically obtained with a minimum increase in material and labor costs.

These and other objects will appear more fully upon consideration of the detailed description of certain embodiments of the invention which follows. In this connection, although several specifically different forms of undergarment are described and illustrated in the accompanying drawings, it is to be expressly understood that these drawings are for purposes of illustration only and are not to be construed as defining the scope of the invention, for which latter purpose reference should be had to the appended claims.

Referring now to the drawings, wherein like reference characters indicate like parts throughout the several views:

Fig. 1 is a front view of a man's undergarment of the midlength or short-legged style embodying the invention, showing the garment as it appears in flattened, undonned condition;

Fig. 2 is a rear view of the garment shown in Fig. 1;

Fig. 3 is a plan view of the pieces of material comprising the garment of Fig. 1, exclusive of the waistband and reinforcing or supporting members later described, shown in detached, flattened condition prior to assembly;

Fig. 4 is a front view similar to Fig. 1 of a modified form of midlength garment constituting another embodiment of the invention;

Figs. 5, 6 and 7 are views similar to Figs. 1, 2 and 3 of a brief or legless type undergarment representing still another modification of the invention; and

2

Fig. 8 is a fragmentary view of a piece of material comprising the body of a brief type garment constituting a variation of the construction illustrated in Fig. 7.

With reference first to Figs. 1, 2 and 3, the undergarment shown therein comprises a main body portion 11 adapted to cover substantially all of the trunk of the wearer between the waist and the crotch with the exception of the front central portion and the crotch, a pair of similarly shaped, overlapping, fly- and crotch-forming front pieces or inserts 12 and 13 and a triangular front piece 14 secured to the lateral edges of the body portion 11 and completing the front and crotch of the garment, a waistband 15 secured to the upper edges of the body 11 and front piece 14, and a pair of strap-like reinforcing or supporting members 16 and 17 extending from the crotch to the waist, overlying the seams connecting the front pieces 12, 13 and 14 to the body 11, and secured to the edges of said elements and to the waistband 15. In this embodiment, the body 11 also has formed integrally therewith depending leg portions 18 and 19 adapted to encase the upper portions of the thighs of the wearer.

It will be apparent from the disclosure herein that the front pieces 12 and 13 are not "inserts" in the meaning frequently attributed to that word in the underwear art; i. e., a gusset or crotch piece inserted in a garment for the purpose of providing additional material at certain points or a different direction of stretch than is provided by the rest of the garment. Instead, they are parts of the front of the garment, also extending through the crotch and upwardly in the rear as hereinafter described, and in combination with the reinforcing members provide the well supported fly, crotch and pouch construction which is an important feature of the garment of the present invention. However, for convenience of description, the pieces 12 and 13, and their counterparts in the other embodiments, may be referred to hereinafter as "inserts."

The body 11 is preferably formed of a unitary piece of knitted material having the wales thereof extending substantially vertically or longitudinally of the garment, as indicated at 20, so that the garment is stretchable in a horizontal or lateral direction in order to snugly fit the body of the wearer, but is substantially non-stretchable vertically. The inserts 12 and 13 and the front piece 14 are made of the same material as the body 11, and also have substantially vertically extending wales. If desired, the front piece 14 could be made integral with the body 11 along one of its inclined side edges, or with one of the

inserts 12 and 13 at its apex; either of such constructions, however, would be more wasteful of cloth than that illustrated. The waistband 15 may be of any suitable construction and material, but is preferably formed of a continuous piece of elastic webbing.

As will be seen best in Fig. 3, the piece of material from which body 11 is formed is generally rectangular in outline when in flattened condition, but has its edges so shaped as to cooperate with the waistband 15, inserts 12 and 13 and front piece 14 to provide a garment covering the trunk of the wearer between the waist and the crotch, and also the upper portions of the thighs.

In the form shown, each of the lateral edges 21 and 22 has an upper diagonally extending portion to which one of the inclined side edges of the front piece 14 is sewn, an intermediate curved portion to which the inserts 12 and 13 are secured, and a lower vertical portion which is adapted to be sewn to one of the lateral edges 23 and 24 of a cut-out 25 in the central portion of the lower edge 26 to form one of the leg portions 18 and 19. The lateral edges 21 and 22 are notched at 27 and 28, respectively, to indicate the points at which the leg seams 29 and 30 begin and the seams between the inserts 12 and 13 and the lateral edges 21 and 22 of the body 11 end; the corresponding points of the inserts 12 and 13 are indicated at 31 and 32.

The inserts 12 and 13 are of identical pattern, but are laterally reversed when the garment is assembled, each consisting of a front, fly-forming portion 33 having one convex edge 34 and one concave edge 35 extending downwardly from the upper end 36, an intermediate crotch-forming portion 37 both of the edges of which are concave, and an enlarged bulbous portion 38 which, when the garment is assembled, is adapted to extend upwardly in the rear of the garment above the point of the crotch and to be secured to the rear central portion of the lower edge 26 of body 11 along a curved seam 39. The curvature of the seam 39 is such that, even though the seam itself is non-extensible, it nevertheless permits relatively unrestricted lateral stretching of the material of both the body 11 and the enlarged bulbous portions 38 of the inserts 12 and 13 in the region of said seam.

In the embodiment of the invention illustrated in Figs. 1-3, the junction between the enlarged bulbous portions 38 of inserts 12 and 13 and the lower edge of body 11 is formed by making a vertical slit 40 in the piece of material from which body 11 is formed, said slit extending upwardly from the apex of cut-out 25 for a distance approximately equal to half the periphery of portions 38, flaring the slit material to receive said portions 38, and then sewing the latter to the edges of the slit 40 along the curved or rounded seam 39. By way of example, the slit 40 may be approximately 4½ inches in length in a size 34 garment of the character illustrated in Figs. 1-3. A slit of this length provides, in the finished garment, an extension upwardly into the rear of the body 11 approximately 3¼ inches above the point of the crotch; and since the extension measures approximately 5¾ inches in width at the widest point of bulbous portions 38, there is not only provided an extra amount of material in the seat of the garment which, together with the elasticity resulting from the curved seam 39, permits squatting, sitting and all other normal movements of the body without binding or discomfort, but the flaring of the slit material to accommo-

date insertion of the bulbous portions 38 also automatically sets the leg portions 18 and 19 in outwardly divergent positions, so that when the garment is worn the stretch of the material in the region of the thighs will be perpendicular to the wales, rather than diagonally thereacross as is the case in garments of the same general character heretofore known. The extra material thus provided in the crotch and seat of the garment is indicated by the folds or wrinkles 41 which appear when the garment is in flattened condition, as shown in Figs. 1 and 2.

Although the crotch-forming portions 37 of inserts 12 and 13 are substantially narrower than the other portions of the inserts, having a minimum width of approximately 3 inches in a size 34 midlength garment, for example, the absence of any stretch-preventing means and the integral construction of these portions with the bulbous portions 38 provide adequate fullness for the formation of a resilient, gently supporting pouch or pocket at the point of the crotch. The support is enhanced by the reinforcing members 16 and 17 which extend downwardly from the waistband 15 to the junctions between the curved seam 39 and the inside leg seams 29 and 30 along which the lateral edges 21 and 22 of body 11 below the notches 27 and 28 are united to the edges 23 and 24 of the cut-out 25. Reinforcing members 16 and 17 are preferably in the form of non-extensible tapes which overlie the seams between the body 11, inserts 12 and 13 and front piece 14, crossing one another at the junctions between said front piece and inserts, and are sewn both to said body, inserts and front piece and to the waistband 15.

In the completed garment, the entire periphery of each of the inserts 12 and 13 is sewn to the body 11 with the exception of the concave edge 35 which is left free and preferably covered with a suitable non-extensible binding 42. Since the inserts 12 and 13 are, as previously mentioned, sewn into the body 11 in laterally reversed positions, the concave edges 35 lie on opposite sides of the front center line of the garment and form a conveniently usable fly-closed opening through which access may be had to the interior of the garment.

By constructing the garment in the manner above described, the fly-forming portions 33 and crotch-forming portions 37 of inserts 12 and 13 and the reinforcing members 16 and 17 provide a neat fly-closed front and a comfortable, well supported pouch or pocket, while the extension of the enlarged bulbous portions 38 of the inserts upwardly in the rear of the garment above the point of the crotch, the insertion thereof in the flared slit 40 and the connection thereof to the lower edge of the body 11 along the curved seam 39 not only afford additional cloth in the seat of the garment but also permit relatively unrestricted lateral stretching of the material of the body 11 and inserts 12 and 13 in the region of the seam 39, thus producing a well fitting, comfortable garment capable of allowing full freedom of body movement without binding. Insertion of the enlarged portions 38 of inserts 12 and 13 into the slit 40 also results in an outward set of the leg portions 18 and 19, and a consequent elimination of diagonal stresses in the material of the garment around the thighs, leaving the material free to stretch perpendicularly to the wales and thereby provide maximum elasticity.

Fig. 4 shows a modified form of midlength undergarment which differs from that of Figs. 1-3

only in elimination of the triangular front piece and the cross-over of the reinforcing members, a lengthening of the inserts or front pieces so as to extend all the way to the waistband, and a corresponding change in the shape of the lateral edges of the body of the garment to conform to the lengthened inserts. As shown, the front, fly-forming portions of the inserts 43 and 44 are extended upwardly to the waistband 15 to which their upper edges are secured, thereby replacing the triangular front piece 14 of Fig. 1. The seams between the lateral edges of the inserts 43 and 44 and body 11 are covered by reinforcing members 45 and 46 just as in the embodiment of Figs. 1-3, except that the upper ends of said members do not cross as do members 16 and 17 in Fig. 1, but extend upwardly to the waistband above the fly-closed opening along convergent lines without meeting. In all other respects, the garment of Fig. 4 is of the same construction as that of Figs. 1-3.

Referring now to Figs. 5, 6 and 7, the garment illustrated therein represents an application of the present invention to a below-the-waist garment of the brief or legless type. As in the case of the first-described embodiment of the invention, the garment of Figs. 5-7 consists of a main body portion 47, a pair of similarly shaped, overlapping fly- and crotch-forming front pieces or inserts 48 and 49, a triangular front piece 50, a waistband 51 and a pair of reinforcing or supporting members or tapes 52 and 53, all of which elements are of substantially the same construction, and function and cooperate in substantially the same manner, as the corresponding elements of Figs. 1-3, except for the form of body 47 and the fact that the intermediate crotch-forming portions 54 of inserts 48 and 49 may be relatively narrower than the corresponding portions 37 of inserts 12 and 13.

As shown in Fig. 7, the outline of the piece of material from which body 47 is formed is practically the same as that of the blank of body 11 along the upper edge and downwardly along the lateral edges as far as notches 27 and 28 of the latter (the corresponding points being indicated at 55 and 56, respectively, in Fig. 7). The lower edge 57 of body 47, however, is provided with a pair of relatively large cutouts 58 and 59 on opposite sides of the vertical center line of the blank which form the leg openings 60 and 61 when the garment is assembled, and with a centrally located, oval-shaped cut-out 62 which is adapted to receive the bulbous portions 63 of inserts 48 and 49 and to have its periphery sewn to those of the inserted portions 63 along a curved seam 64 of such curvature as to impose relatively no restriction to lateral stretching of the material of the seat of the garment in the region of said seam. Although the maximum vertical dimension of the cut-out 62 may be the same as that of bulbous portions 63 of inserts 48 and 49, its horizontal or lateral dimensions, and hence its area, are less than those of said portions 63 so that, in the completed garment, there will be an extra amount of material in the seat, as indicated by the wrinkles 65 in Fig. 6, to insure sufficient elasticity to avoid stricture during stooping, sitting and like movements of the wearer.

Ordinarily, an oval-shaped cut-out like that illustrated in Fig. 7 will provide adequate fullness in a brief type garment because such garments do not impose as much restriction on body movements as those of the legged types. However, if desired, additional fullness may be obtained by

substituting for the oval-shaped cut-out 62 of Fig. 7 either a slit like that shown in Fig. 3, or an inverted V-shaped cut-out 66 of the character indicated in Fig. 8.

- 5 Similarly to the construction of Figs. 1-4, the reinforcing members 52 and 53 of the brief type garment of Figs. 5-7 extend downwardly from the waistband 51 to the junctions between the curved seam 64 and the relatively short seams 67 and 68 along which the portions of the lower edge 57 of body 47 outside cut-outs 58 and 59 are united to the central portion of said edge 57 adjacent the cut-out 62, and overlie the seams between the body 47, inserts 48 and 49 and front piece 50.

10 There is thus provided by the present invention an improved form of below-the-waist undergarment embodying a novel crotch construction which both furnishes sufficient fullness of material and elasticity in the crotch and thigh regions to accommodate all normal movements of the body, and contributes to the formation of a resilient, well supported pouch at the crotch. Garments embodying the invention are better fitting and more comfortable than similar garments heretofore known, and require a minimum of material and labor for their manufacture.

15 While several specifically different forms of garment embodying the invention have been described and illustrated in the accompanying drawings, it will be obvious that the invention is not limited to the exact structures shown, but is capable of a variety of mechanical embodiments. For example, the improved crotch construction 20 may be embodied without material change in garments having legs of various lengths other than the midlength type illustrated in Figs. 1-4 and in the below-the-waist portions of union suits, while certain features of said construction are also 25 adaptable to garments for children and women, as well as to men's underwear of the support type. It should also be clearly understood that the dimensions of certain parts which are set forth above are intended as examples only, and may be 30 varied as necessary to produce the desired results in garments of varying types and sizes.

35 Various other changes which will now suggest themselves to those skilled in the art may be made in the form, details of construction and 30 arrangement of the parts without departing from the inventive concept. Reference is therefore to be had to the appended claims for a definition of the limits of the invention.

40 What is claimed is:

- 45 1. An undergarment of the support type for male wear comprising a body formed of a unitary piece of laterally stretchable material adapted to cover the back, sides and portions of the front of the wearer between the waist and the crotch, a waistband secured to the upper edge of said body, and a front piece of laterally stretchable material secured to the lateral edges of said body and completing the front of the garment, said front piece having an integral extension forming 50 the crotch of the garment and extending upwardly in the rear of the garment above the point of the crotch, said front piece being so constructed and arranged as to provide a fly-closed opening in the front of the garment and a pouch therebelow, and also being connected to said waistband 55 so as to support the pouch therefrom, the lower edge of said body being cut upwardly in the rear of the garment to receive the upwardly extending portion of said extension, the area of the upwardly extending portion of said extension being 60

greater than that of the cut so as to provide extra material in the seat of the garment, said cut material and said upwardly extending portion of said extension being sewn together along a curved seam of such configuration that the material of the garment in the region of said seam is relatively free to stretch laterally.

2. An undergarment of the support type for male wear comprising a body formed of a unitary piece of laterally stretchable material adapted to cover the back, sides and portions of the front of the wearer between the waist and the crotch, a waistband secured to the upper edge of said body, and a front piece of laterally stretchable material secured to the lateral edges of said body and completing the front of the garment, said front piece having an integral extension forming the crotch of the garment and extending upwardly in the rear of the garment above the point of the crotch, said front piece being so constructed and arranged as to provide a fly-closed opening in the front of the garment and a pouch therebelow, and also being connected to said waistband so as to support the pouch therefrom, the lower edge of said body having a cut-out in the rear of the garment to receive the upwardly extending portion of said extension, the area of the upwardly extending portion of said extension entering said cut-out being greater than that of the cut-out so as to provide extra material in the seat of the garment, said upwardly extending portion of said extension and said cut-out portion of said body being sewn together along a curved seam of such configuration that the material of the garment in the region of said seam is relatively free to stretch laterally.

3. An undergarment of the support type for male wear comprising a body formed of a unitary piece of laterally stretchable material adapted to cover the back, sides and portions of the front of the wearer between the waist and the crotch, said body also having depending leg portions adapted to encase at least the upper portions of the thighs of the wearer, a waistband secured to the upper edge of said body, a pair of overlapping front pieces of laterally stretchable material secured to the lateral edges of said body and completing the front of the garment, said front pieces being so constructed and arranged as to form a fly-closed opening in the front of the garment and a pouch therebelow, said front pieces having superposed extensions formed integrally therewith forming the crotch of the garment and extending upwardly in the rear of the garment above the point of the crotch, the upwardly ex-

tending portions of said front pieces being wider than the crotch-forming portions, the lower edge of said body being slit vertically in the rear of the garment and the slit material flared to receive the upwardly extending portions of said extensions, said slit material and said upwardly extending portions of said extensions being sewn together along a curved seam of such configuration that the material of the garment in the region of said seam is relatively free to stretch laterally, the insertion of the upwardly extending portions of said extensions in the slit providing extra material in the seat of the garment and producing an outward set of said leg portions, and a pair of substantially non-extensible reinforcing members extending from the crotch to the waistband and secured to the lateral edges of said front pieces and to said waistband, said members providing support for the pouch from the waistband.

4. An undergarment of the support type for male wear comprising a body, a waistband, and a front piece of laterally stretchable material extending from the waistband downwardly in the front of the garment to and through the crotch and upwardly in the rear of the garment above the point of the crotch, said front piece being so constructed and arranged as to provide a fly-closed opening in the front of the garment and a pouch therebelow, and also being connected to said waistband so as to support the pouch therefrom, the portion of said front piece which extends upwardly in the rear of the garment being wider than the crotch-forming portion thereof and being sewn to the body of the garment along a curved seam of such configuration that the material in the region of said seam is relatively free to stretch laterally.
